UNITED STATES PATENT OFFICE.

HENRY MULLER, OF EAST ORANGE, NEW JERSEY.

CARD-INDEX.

1,350,665.

Specification of Letters Patent. Patented Aug. 24, 1920.

Application filed August 8, 1918. Serial No. 248,982.

To all whom it may concern:

Be it known that I, HENRY MULLER, a citizen of the United States, residing in East Orange, Essex county, New Jersey, have invented certain new and useful Improvements in Card-Indexes, of which the following is a specification.

The invention is an improvement in card indexes and comprises more particularly a combination whereby a plurality of cards having tabs at their tops may be sorted in a common container to cause their tabs to occupy a plurality of columns corresponding to a desired classification. The system is especially useful, for example, for the purpose of keeping track of meters in the business of gas and electric companies, but many other fields exist for its employment.

In the accompanying drawings illustrating the invention:

Figure 1 is a plan view;

Fig. 2 is a vertical transverse section through the box, showing a card in dotted lines, leader lines and designations being employed to indicate the series of tab column positions and the corresponding card notches which are engageable with the positioning member 7 to bring the tabs into these columns;

Fig. 3 is a vertical section in a fore and aft plane;

Figs. 4 and 5 are fragmentary perspective views; and

Fig. 6 is a face view of one of the cards.

The cards 1 are provided each with an upstanding tab 2 at the left-hand end, these tabs bearing distinguishing marks of suitable kind as indicated. The faces of the cards have suitable tabulation spaces and indicia; and in their lower portions are a series of comparatively deep cuts 3, preferably of V or tapered form, these cuts being in the same arrangement in all of the cards. Each card is provided with an alining and guiding edge 20. The tab 2 is arranged in one definite position on each card which is the same relative position with respect to the ends of the cards for all of the cards. In the drawing the tab is shown at one end of each card and may be provided with an alining edge 21. Each tab is thus arranged in a fixed and predetermined relation to the series of notches. The cards may thus be arranged with the tabs in line one behind the other when starting the sorting operation, and thereafter the cards may be

grouped with the tabs alined and arranged to indicate respective groups while the classification is progressing.

The box, tray or drawer 4 is of sufficient width to permit the cards to be shifted laterally, i. e. in the direction of their lengths, to be sorted into a multiplicity of overlapping positions, with their tabs in rows, as seen in Fig. 1. At front and back the box is preferably provided with downwardly and inwardly sloping walls 5 and 6.

In the lower part of the box is an elevated fore and aft positioning member 7 adapted to be selectively engaged by the cuts 3 so as to cause the tabs of the respective cards to fall into the desired rows or columns and to prevent accidental lateral displacement therefrom. In the particular instance selected for illustration there are seven cuts in each card (including a half notch at the right end) and seven rows within which the tabs may lie. The spacing of the cuts and therefore of the columns may be varied. If desired the columns may be designated in some suitable way upon the box, as for instance, by characters or legends upon the back of the box, as suggested in Figs. 1 and 2.

The positioning member 7 as herein illustrated, consists of a knife-like blade, tapering upward to a comparatively sharp or narrow edge, which in connection with the V-form of the cuts facilitates the guiding of the cards. The edge of this member is a substantial distance above the bottom of the box, and obviously its lower portion might be omitted, leaving a space between the member and the bottom.

The invention also provides movable means extending over the tops of the cards for guiding them to their places and preventing dislodgment from the box. Such means may be varied, but preferably comprises one or more bars 8, the ends of which may be entered into sockets 9 and 10, which are arranged in two lines at front and back of the top of the box, the locations of these sockets corresponding to the possible positions of the left and right hand ends of the cards and their spacing corresponding to the spacing of the notches in the bottoms of the cards. The rear row of sockets has an overhanging rear ledge 11, beneath which the rear end of the bar extends, and locking means are provided in connection with the front row, which means may take vari-

ous forms, but is preferably embodied as a slide 12 extending along the upper edge of the wall member 13 in which the sockets 9 are formed, this slide having notches 14 adapted to register with the open tops of the sockets 9 in one position of the slide, and to close the same when moved from such position. A turned-up end 15 on the slide serves as a suitable operating handle, and 10 the slide may be held against unintended displacement by frictional engagement beneath the heads of screws 16, which stand in guiding relation in slots 17 in the slide, or if desired some positive holding means 15 may be provided.

When cards are being sorted against either the left or right hand walls of the box, the guide bar or bars are not used. For an intermediate column, however, the bar is 20 placed in the corresponding pair of notches, and locked, and in placing cards in that group all that is necessary is to slide their left or right alining and guiding side edges or ends down along the bar. This will 25 cause the proper cut 3 to take over the member 7, and even though the movement be not perfectly vertical the particular formation of the cut and member will insure the desired engagement.

30 The bars 8 also constitute a locking means, which may be placed in two of the pairs of sockets so as to retain all the various overlapping groups extending beneath it against coming out.

35 The system can be used for many different purposes and in different ways. The following explanation of one will be suggestive of its possibilities.

Gas and electric companies badge or number 40 their meters, each division having its own series of numbers. A division that has 125,000 meters would, of course, number these meters from 1 to 125,000. But a division is divided into districts and the meters 45 are set in the different districts.

Under the present system, meters, when 50 set and removed, are entered on meter record books. The districts in which they are set are designated by numbers 1-2-3-4, as 55 the case may be. When an audit is made or when the meters in stock are to be marked against the inventory it is necessary to search through the books to find meters in certain districts or meters which are in stock. This is a very slow and unsatisfactory process, open to errors, especially when the meters have been set and removed a number of times and there are several entries in the same block or account. The present 60 index will greatly facilitate this work.

Let it be assumed that there is a division with five districts. For this division there would be used a box or system with seven columns, one column for each district, one 65 column for meters in stock checked, and one

column for meters in stock unchecked. By a column is meant a row of tabs. Let it be assumed that the first column to the left is for district 1, the second for district 2, the third for district 3, the fourth and fifth for 70 districts 4 and 5, the sixth for stock checked, and the seventh for stock unchecked. Obviously the uses of columns six and seven can be reversed, and likewise the uses or order of any or all of the columns may be changed. 75 Additional columns may, of course, be provided for.

In the illustration, before any meters are set the cards would be to the right in the box. Now suppose a number of meters are 80 to be set in district 2. The operator may insert and lock one of the guide bars in the second pair of sockets from the left. This will make it impossible to put any card into the first row or column. Suppose the first 85 meter set is 25,603. The operator finds and takes out the corresponding card, makes the necessary entry on it, and replaces it in the box, sliding its left end down against the bar. 90

When meters are removed, say from district 3, one of the guide bars is inserted and locked in the third position from the left. This makes it impossible to take out any card the tab of which is to the left of the 95 guide bar. This helps to avoid error. The operator finds the card, makes the removal entry on the same, and replaces it in the box, sliding its right-hand edge downward in contact with the right-hand side of the box. 100

When checking meters in stock against the inventory, the operator may insert and lock one of the guide bars in the sixth position from the left. He finds the cards for the meters as they appear on the inventory, 105 compares and checks, and replaces the cards, sliding them against the guide bar into the column "stock checked." When all the meters on the inventory are checked all the cards must be resting against the guide bar. 110 To make a misplacing of a card almost impossible the cards for different trays may be of different colors. Boxes can be made for any desired number of columns, and for any number of cards, limited only by the size of 115 the cards.

Instead of operating against a guide bar at the left, the cards may be inserted along a bar properly positioned at the right. When one of the bars is serving as a guide, 120 the other may be placed as a retainer to keep cards not involved in the transfer from being accidentally removed or displaced. When not in use the bars may be placed in the extreme right and left hand 125 pairs of notches over the sides of the box. In transferring cards from one column to another the bars may be placed in the appropriate positions, one to the left and the other to the right, inwardly of the ends of 130

the box, and the cards removed upward in contact with one bar and inserted downward in contact with the other bar, the bars thus reducing the effective length of the 5 box as far as the transfer is concerned. When inserting the cards against a right-hand bar as a guide, it will be noted that the elevation of the positioning member 7 at the bottom is sufficient to insure engagement 10 with the proper notch before the edge of the card has passed downward out of guiding engagement with the bar. In other words, the distance between the top and bottom guides is always less than the height 15 of the coöperating guiding edge of the card. As indicated at 21, the tabs may be set in slightly from the left-hand guiding edge 20 of the cards.

What I claim as new is:

20 1. In a device of the class described, the combination of cards having series of notches in their lower edges, a box in which said cards may be shifted laterally, a longitudinal positioning member with which said notches may be selectively engaged, and a laterally movable guide extending lengthwise to the holder and arranged at the top of the box and above the tops of the cards thereby facilitating the engagement of the 25 selected notches with said positioning member.

2. In a device of the class described, the combination of cards having series of notches in their lower edges, a box in which 30 said cards may be shifted laterally, a fore and aft positioning member with which said notches may be selectively engaged, and laterally movable means extending lengthwise to the holder and arranged at the top 40 of the box and above the tops of the cards for guiding the cards into engagement with the positioning member.

3. In a device of the class described, the combination of cards having series of 45 notches in their lower edges, a holder in which said cards may be shifted laterally, a fore and aft positioning member with which said notches may be selectively engaged, a guide facilitating the engagement 50 of the selective notches with said positioning member, and means determining a series of positions of the guide member corresponding to the series of notches in the cards.

4. A card index comprising cards having 55 plural notches in their lower portions, a box wherein the cards may be shifted sidewise, a fore and aft positioning member in the lower part of the box adapted to be selectively engaged by said notches, and a movable bar at the top of the box and above the tops of the cards adapted to guide the ends of the cards as they are slid down into engagement with the positioning member.

5. A card index comprising cards having 60 plural notches at the bottom, a box wherein

the cards may be shifted sidewise, a fore and aft positioning member in the lower part of the box adapted to be selectively engaged by said notches, a movable bar at the top of the box and above the tops of the cards adapted 70 to guide the ends of the cards as they are slid down into engagement with the positioning member, and means for locking said bar in a position where it holds the cards in place.

6. A card index comprising cards having plural notches at the bottom, a box wherein the cards may be shifted sidewise, a fore and aft positioning member in the lower part of the box adapted to be selectively engaged by said notches, a movable bar above the tops of the cards, means providing a series of sockets at the front and a corresponding series at the back of the box to receive the ends of said bar, said sockets 80 being in positions corresponding to the various possible positions of the ends of the cards as determined by the arrangement of the notches therein, and means for holding the bar in the sockets.

7. A card index comprising cards having plural notches at the bottom, a box wherein the cards may be shifted sidewise, a fore and aft positioning member in the lower part of the box adapted to be selectively engaged by the notches in the cards, a movable fore and aft guide bar at the top of the box, and means for holding said guide bar in a series of positions corresponding to the various locations of the ends of the cards as determined by the coöperation of the notches and positioning member, said means comprising sockets at front and back of the box, and a locking slide coöperating with one series of sockets.

8. Card index apparatus comprising a box wider than the cards to be accommodated, fore and aft positioning means in the lower part of the box, series of sockets at the top of the box at front and back, and one or 110 more guide and guard bars coöperative with said sockets.

9. Card index apparatus comprising a box wider than the cards to be accommodated, fore and aft positioning means in the lower 115 part of the box, series of sockets at the top of the box at front and back, one or more guide and guard bars coöperative with said sockets, and means for locking said bars.

10. A card index comprising cards having notches in their lower portions, a box wider than the cards and having elevated guiding and positioning means disposed fore and aft in its lower part, and one or more movable guide bars at the top, the vertical distance 125 between the upper and lower guides being less than the height of the guiding edges of the cards.

11. A card for card indexes, said card having a series of spaced notches in its lower 130

- edge and provided with an alining side edge located in a predetermined, fixed relation to said series of spaced notches, said card carrying an index tab located at the same end 5 of the said card as the alining side edge, said tab being thus arranged in a fixed and predetermined relation to the series of notches.
12. A set of cards for a card index, each card being provided with a series of spaced 10 notches located in its bottom edge and having an alining side edge, each of said cards carrying an index tab arranged at the same

end of said card as the alining side edge, each of said tabs being thus arranged in a fixed and predetermined relation to the 15 series of notches.

In testimony whereof, I have signed my name to this specification, in the presence of two subscribing witnesses.

HENRY MULLER.

Witnesses:

ANNA M. MULLER,
C. H. MULLER.
